US0D1088829S

(12) **United States Design Patent** (10) **Patent No.:** **US D1,088,829 S**
(45) **Date of Patent:** **** Aug. 19, 2025**

(54) **PULLEY**

(71) Applicant: **CVF Motorsports, Inc.**, New Prague, MN (US)

(72) Inventor: **Joseph K. Vail**, Lonsdale, MN (US)

(73) Assignee: **CVF Motorsports, Inc.**, New Prague, MN (US)

(**) Term: **15 Years**

(21) Appl. No.: **29/945,135**

(22) Filed: **May 31, 2024**

(51) **LOC (15) Cl.** **08-11**

(52) **U.S. Cl.**

USPC **D8/360**

(58) **Field of Classification Search**

USPC D12/204, 209-212; D8/360, 360.1,

D8/356-359

CPC B65H 75/00; B65H 75/40; B60B 1/00;

B60B 1/08; B60B 3/00

(57) **CLAIM**

The ornamental design for a pulley, as shown and described.

DESCRIPTION

FIG. 1 is a front perspective view of a pulley of my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Where included, broken lines showing environment or structure are for illustrative purposes only and form no part of the claimed design.

1 Claim, 6 Drawing Sheets
